UNITED STATES PATENT OFFICE

WILHELM K. MOLL, OF CHICAGO, ILLINOIS, ASSIGNOR TO DITTO, INCORPORATED, OF CHICAGO, ILLINOIS, A CORPORATION OF WEST VIRGINIA

SWINGING MARGIN BAR

Application filed October 9, 1929. Serial No. 398,327.

The invention relates to duplicating machines of the hektograph type and has reference more particularly to that class of such machines employing a flat printing bed supported on a suitable frame, a duplicating band or apron stretched thereover between receiving and delivery spools, and an impression device including a platen carriage which is adapted to be rolled over the bed in order to 10 impress both the master and copy sheets on that portion of the gelatine apron which is supported by the bed.

Hektograph machines find extensive use in office work, and especially in billing operations where it is desired to duplicate a large number of bills to insure accurate and efficient checking methods as, for example, in utility companies which issue a large number of monthly bills to their customers in duplicate 20 form as well as retaining duplicates of the bills for their own files. To insure, in these billing operations, accurate positioning and aligning of the master sheets with the forward edge of the gelatine band so that the 25 duplicate copies, after impression upon the gelatine, will be provided with adequate marginal edges, the machines are equipped with margin bars generally mounted within the frame of the machine at the forward end and 30 parallel with the surface of the gelatine band.

One of the primary objects of the present invention is to provide hektograph machines with an improved means for accurately positioning the master sheets and copies upon the 35 surface of the gelatine bands and which will be adapted, upon actuation of the platen carriage to begin its printing strokes, to swing from a normal operating position to an inoperative position.

40 A more specific object of the present invention is to provide hektograph machines with a novel type of margin bar that will remain in inoperative position out of the way of the operator during the printing operation, thus providing for easy access to the forward edge of the master sheets and copies during the printing stroke of the platen carriage.

Another object is to provide a margin bar 50 having operative and inoperative positions

with respect to the platen carriage, and novel means for actuating the bar in accordance with the travel of the platen carriage.

A yet further object is to provide a margin bar which will be simple and durable in construction, economical in manufacture and reliable in operation. 55

With these and various other objects in view, the invention may consist of certain novel features of construction and operation, 60 as will be more fully described and particularly pointed out in the specification, drawings and claims appended hereto.

In the drawings, which illustrate an embodiment of the device and wherein like reference characters are used to designate like parts— 65

Figure 1 is a fragmentary sectional view of the forward end of a hektograph machine showing the margin bar in operative position; 70

Figure 2 is a sectional view similar to Figure 1 showing the margin bar in inoperative position; and

Figure 3 is a perspective view of the margin bar shown mounted within the frame of the machine. 75

The side members 10 constituting the frame of the machine have secured therein by any suitable securing means the flat platen or 80 supporting bed 12 for accommodation of the gelatine band 14 which is stretched or mounted thereover. Adapted to travel back and forth over the exposed surface of the gelatine band is a platen carriage designated in its 85 entirety at 16. To facilitate the movement of the carriage, one of the side members 10 is generally provided with a suitable guide rail, and the carriage is equipped on one side with a guiding member for sliding engagement 90 with the rail. This structure constitutes standard equipment on hektograph machines and is therefore not shown in detail, inasmuch as it forms no part of the present invention. Journaled within the end frames 95 18 of the platen carriage in proximity to the gelatine surface is a plurality of impression and stripping rollers 20 and 22 which are adapted, upon actuation of the carriage handle 24, to be spaced sufficiently to allow 100

insertion of the forms or copies designated at 26 between them, and, upon further actuation of the handle, to assume their closed or operative position. This actuation of the 5 carriage handle not only operates to provide for spacing of the rollers as described, but also operates upon the roller 20 to raise the roller from the surface of the gelatine band 14 so that the forms or copies 26 will slide 10 beneath the roller upon insertion and abut the stops on the margin bar 30 to be herein-after more fully described.

Referring to Figure 3, the bar is shown 15 comprising the base plate 32, the integral end members 34 and the rear ledge 36. The bar is pivoted at 38 by bolts 40 passing through the end members and secured in the supporting blocks 42 which are in turn fastened by bolts or other suitable means in the side members 10. The margin bar is so pivoted and balanced by the base plate 32 and the additional weights comprising the margin stops 34, that normally the bar will hang so that the plate 32 is on an incline sloping from 20 left to right which maintains that edge of the plate 32 adjacent the margin stops slightly below the surface of the gelatine band as shown in Figure 2. This constitutes the inoperative position of the bar.

30 To cause the margin bar to assume its operative position, a dog 46 is provided having pivotal engagement with the supporting blocks at 48 and equipped with a cam 50 for camming engagement with the forward and 35 sloping surface 52 of the end members 34. In the operation of the machine, as the carriage reaches the forward end or the end of its travel in a direction toward the operator, the cross rail 54 will engage the sloping end 40 of the dog 46 causing it to dip and giving a consequent clockwise movement to the cam 50. This movement of the cam towards the end members results in the plate 32, and consequently the edge adjacent the stops 44, 45 being elevated until the carriage reaches its extreme forward position, when the edge will be on a line with the upper surface of the gelatine band 14 as disclosed in Figure 1.

In this position the rollers 20 and 22 are 50 adapted to be spaced by actuation of the handle 24 and the duplicate copy removed. Another blank copy is then inserted between the spaced rollers and under the roller 20 until its forward edge abuts the stops 44 on the 55 margin bar 30 which properly positions the copy with respect to the edge of the gelatine band, when the rollers can then be closed and the printing stroke of the carriage begun. This operation requires the carriage to travel 60 rearward or away from the operator, thus impressing the blank copy upon the surface of the gelatine band and, at the same time, releasing the dog 46 from under the cross rail 54 which, of course, allows the margin bar to swing into its inoperative position.

By referring to Figure 2 it will be seen that in this position the forward edge of the copy is exposed since the plate 32 has dropped below the level of the gelatine surface which provides for easy access to the edge of the copy during the printing stroke of the carriage when it may be necessary to strip the duplicate copy from the gelatin band, as is often the case in duplicating bills and other master sheets of the same or smaller size.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a duplicating machine the combination with a printing bed, a platen carriage adapted to travel over said bed, a margin bar pivoted to said machine at one end of said bed, and adapted to swing from an operative position to an inoperative position with respect to said carriage, actuating means for said bar including a pivoted dog having engagement with said bar, and means on said carriage adapted to depress or release said dog.
2. In a duplicating machine the combination with a printing bed, a platen carriage adapted to travel over said bed, a margin bar pivoted to said machine at one end of said bed, and adapted to swing from an operative position to an inoperative position with respect to said carriage, paper stop devices secured to said bar and adapted to position a sheet of paper or the like upon said bed after insertion in said carriage when in operative position and to expose the edge of said sheet when in inoperative position, actuating means for said bar including a pivoted dog, and means on said carriage adapted to depress or release said dog.
3. In a duplicating machine the combination with a printing bed, a platen carriage adapted to travel over said bed, means for positioning a sheet of paper upon said bed after insertion in said carriage including a margin bar pivoted to said machine, and a pivoted dog for actuating said bar to cause it to assume an inoperative position during the printing stroke of said platen carriage.
4. In a duplicating machine the combination with a printing bed, a platen carriage adapted to travel over said bed, means for positioning a sheet of paper upon said bed after insertion in said carriage including a margin bar pivoted to said machine, and a pivoted dog for actuating said bar to cause it to assume an inoperative position during the printing stroke of said platen carriage.

and an operative position at the completion of said stroke.

5. In a duplicating machine the combination with a printing bed, of a platen carriage 5 adapted to travel over said bed, a margin bar at one end of said bed and adapted to swing from an operative to an inoperative position with respect to said carriage, and actuating means for said bar including a dog 10 adapted to be engaged by said carriage.

6. In a device of the class described, in combination with a printing bed and a platen carriage adapted to travel over said bed, a pivoted margin bar having operative and in- 15 operative positions with respect to said printing bed, and means for actuating said bar including a pivoted dog having engagement with said bar and means on said carriage adapted to depress and release said dog.

20 7. In a device of the character described, in combination a margin bar having a horizontal operative position and a sloping inoperative position, comprising a base plate provided with paper stop devices, end mem- 25 bers integral with said base plate, and means for pivotally securing said end members to allow said bar to assume a sloping inoperative position.

8. In a device of the character described, 30 in combination a margin bar having a horizontal operative position and a sloping inoperative position, said bar comprising a base plate with upstanding end members secured to said base plate, supporting blocks to which 35 said end members are pivotally secured, and a dog pivoted to said blocks and adapted to have camming engagement with said end members, whereby actuation of said dog locates said bar either in operative or inoper- 40 ative position.

Signed at Chicago, Illinois, this 5th day of October, 1929.

WILHELM K. MOLL.
